DESIGN FOR A TRACTOR CARRIED MATERIAL HANDLER OR THE LIKE

Curtis C. Baldwin, Ottawa, Kans.

Application October 31, 1942, Serial No. 108,658

Term of patent 7 years

To all whom it may concern:

Be it known that I, Curtis C. Baldwin, a citizen of the United States, residing at Ottawa, in the county of Franklin and State of Kansas, have invented a new, original, and ornamental Design for a Tractor Carried Material Handler or the like, of which the following is a specification, reference being had to the accompanying drawing forming a part thereof.

Fig. 1 is a side elevational view of the tractor carried material handler or the like, showing my new design.

Fig. 2 is a top plan view thereof; and
Fig. 3 is an end elevational view thereof.

The dot-and-dash line showing of a tractor in the several drawing figures, is for illustration purposes only.

I claim:

The ornamental design for a tractor carried material handler or the like, as shown and described.

CURTIS C. BALDWIN.
